UNITED STATES PATENT OFFICE

JAMES ALLEN WORDEN, OF ANTIGO, WISCONSIN

KILN

Application filed June 24, 1929. Serial No. 373,398.

This invention relates to improvements in kilns, and more particularly to kilns for drying and seasoning lumber.

In lumber kilns as now used it is very difficult, if not impossible, to maintain within the kiln throughout its entire length, a drying medium of a uniform temperature. The result is that lumber disposed within the kiln is subjected to uneven temperature conditions, and perfect drying and seasoning of the lumber does not result, and checking is apt to occur.

In the present invention a closed circuit of air is utilized, and said air is heated prior to its introduction into the kiln proper, and the hot air carrying conduits are gradually diminished in cross-sectional area away from the heating unit, and the flue vents into the kiln proper are increased in size as their distances from the heating unit increases, with the result that throughout the entire length of the kiln the heating medium is discharged into the kiln proper with as little pressure and temperature variance as is possible. Also, the cold air or return conduits increase in cross-sectional area toward the heating unit to accommodate the incoming cooled air and to maintain a constant pressure. Hence, through this arrangement, the present invention aims at the elimination of the above-mentioned objection by maintaining a drying medium of a constant temperature and pressure in any portion of the kiln, whereby satisfactorily dried and seasoned lumber will result.

A further object of the invention is to provide a lumber kiln which will receive lumber-loaded flat cars and which may be readily divided into individual compartments, if desired.

A further object of the invention is to provide a lumber kiln which is of very simple construction, is relatively inexpensive to build and operate, is efficient, is strong and durable, and is well adapted for the purposes described.

With the above and other objects in view, the invention consists of the improved kiln, and its parts and combinations as set forth in the claims, and all equivalents thereof.

In the accompanying drawings in which the same reference characters indicate the same parts in all of the views:

Fig. 1 is a horizontal sectional view of the improved kiln;

Fig. 2 is a cross-sectional view taken on line 2—2 of Fig. 1;

Fig. 3 is a longitudinal sectional view taken on line 3—3 of Fig. 1;

Fig. 4 is a longitudinal sectional view taken on line 4—4 of Fig. 1; and

Fig. 5 is a cross-sectional view taken on line 5—5 of Fig. 1.

Referring now more particularly to the drawings, it will appear that the numeral 8 indicates an enclosure mounted on foundation or supporting members 9 and forming the main kiln structure, said structure being elongated and of a height sufficient to accommodate therewithin piles of lumber or lumber-piled flat cars. Within said kiln structure are one or more longitudinally extending platforms 10 carrying spaced car rails or tracks 11 on which flat cars 12 are adapted to travel.

An enclosure 13 adjoins the main kiln structure and extends lengthwise of one side thereof. Within said enclosure 13 is a heating chamber 14 containing heating coils 15 through which a heating medium is circulated. One end wall of the heating chamber is provided with a circular opening 16 in which is mounted a fan 17 enclosed by the end portion of a hot air flue 18 which terminates at the heating chamber and surrounds the fan opening 16.

As shown clearly in Fig. 1, the hot air flue 18 is formed with a right angular bend and the major portion of said flue extends transversely to the kiln structure at the inner end thereof and below the platforms 10. Below each platform 10 is a longitudinally extending hot air conduit 19 and said conduits open at their inner ends into the transverse portion of the flue 18. Said conduits 19, as illustrated in Figs. 3 and 4, are relatively deep at their inner end portions and the bottom members of said conduits are inclined upwardly toward the rear or outer end of the kiln structure, whereby the con-

duits are of rearwardly decreasing depth, and the cross-sectional area of the same, of course, rearwardly decreases.

Each platform 10 is provided with spaced 5 apart hot air outlet openings 20, and as shown in Fig. 1, the size of said outlet openings of each line is rearwardly increased.

The result of the arrangement thus far described is that air is heated within the 10 heating chamber 14 by the coils and the heated air is drawn out of the heating chamber by the fan 17 and is forced through the hot air flue 18, from whence it passes into the hot air conduits 19. At the front or inner ends of the conduits the pressure is the 15 greatest, and therefore, smaller outlet openings 20 are required to discharge an adequate amount of hot air into the kiln proper. Also, within the forward end portions of 20 said conduits enough heating medium must be retained to supply the remaining portions of the conduits, and hence said conduits are enlarged at their forward ends and gradually are reduced toward their rear ends. As 25 the hot air passes through the gradually reduced portions of said conduits the pressure thereon decreases and the outlet openings 20 are progressively larger to discharge heated air into portions of the kiln proper. Also 30 the supply of hot air within said conduits is gradually reduced and therefore the size of the conduits therefor may be reduced and the reduction in the size of the conduits will increase the pressure on the air therein. 35 This arrangement, therefore, tends to equalize, as much as is possible, the amount, temperature and pressure of air admitted into the kiln throughout various portions of its length, whereby lumber within the kiln will 40 be effectively dried and seasoned and will not check.

Between the platforms 10 and along the outer sides thereof are cooled air return conduits 21, which conduits are open at their 45 tops, and their bottom walls are rearwardly or outwardly, downwardly inclined, whereby the cross sectional area of each conduit 21 is gradually increased toward the rear end of the kiln. As shown in Figs. 3 and 4, the inclination or taper of the conduits 21 is exactly opposite to that of the conduits 19. As the air cools within the kiln it sinks and will enter adjacent portions of the conduits 21 as the circulation therein establishes a suction. Obviously, toward the rear of the kiln there is a greater amount of air to be accommodated by the conduits 21 for return, and hence the increase in their size. 50 The conduits 21 open at their rear end portions into a transverse cooled air flue 22 which underlies the rear end portions of the platforms 10, and said flue 22 extends into the enclosure 13 with a right angularly bent 55 portion therein, and a flue portion 22' en-

ters a side of the heating chamber 14 opposite to the outlet side.

In the improved kiln, the principle of a closed circuit of a fluid is utilized and the circulation is kept active by the fan 17 which forces the heating medium from the chamber 14 into the flue 18 and conduits 19, and causes cooled air to be drawn into the conduits 21, and through the same and the flues 22 and 22' back to the heating chamber for re- 70 heating.

It will be noted that the front of the kiln structure, coincident with the platforms 10, is provided with hinged doors 23 to allow the passage of the flat cars 12 therethrough 75 on the tracks 11. A plurality of flat cars having green lumber piled thereon may be received within the kiln, and each flat car is preferably stationed over an opening 20.

If desired, the interior of the kiln may be 80 divided into separate compartments by means of canvas curtains 24, slidably depended at spaced intervals from rods 25. When not in use, said curtains may be pushed aside so as not to restrict longitudinal travel with- 85 in the kiln structure.

It is to be understood that the improved kiln is not to be limited only to the conditioning of lumber and forest products, but it may also be used for the drying of celutex 90 and other organic and inorganic materials, as well as for the hydration and dehydration or conditioning of chemicals, minerals and other products and materials.

From the foregoing description it will be 95 seen that the improved lumber kiln is of simple and novel construction, and is well adapted for the purposes set forth.

What is claimed as the invention is:

1. In a kiln, an enclosure, a heating unit 100 thereadjacent, an outlet flue, a return flue, said flues extending between opposite ends of said enclosure and the heating unit, and a pair of conduits extended between said flues and communicating with the same and with the interior of the enclosure, said conduits being oppositely tapered.

2. In a kiln, an enclosure, a heating unit 105 thereadjacent, a warm air flue, a cooled air return flue, said flues extending between opposite ends of the enclosure and the heating unit and in communication with the latter, a warm air conduit extending lengthwise of the enclosure between said flues and communicating with the warm air flue, the cross-sectional area of said warm air conduit being gradually decreased from the warm air flue to the return flue, said conduit also being formed with spaced apart discharge 110 openings increasing in size from the warm air flue to the return flue, and a cooled air return conduit paralleling the first-mentioned conduit and connected with the return flue and being gradually increased in cross- 115 sectional area from the warm air flue to the 120 return flue.

3. In a kiln, an enclosure, a heating unit 125 thereadjacent, a warm air flue, a cooled air return flue, said flues extending between opposite ends of the enclosure and the heating unit and in communication with the latter, a warm air conduit extending lengthwise of the enclosure between said flues and communicating with the warm air flue, the cross-sectional area of said warm air conduit being gradually decreased from the warm air flue to the return flue, said conduit also being formed with spaced apart discharge 130 openings increasing in size from the warm air flue to the return flue, and a cooled air return conduit paralleling the first-mentioned conduit and connected with the return flue and being gradually increased in cross- 135 sectional area from the warm air flue to the return flue.

return flue, said cooled air conduit having an elongated opening to admit cooled air from the enclosure at any point along its length.

3. In a kiln, an enclosure having an elongated platform therein, a heating unit adjacent said enclosure, a warm air flue, a cooled air return flue, said flues extending between opposite ends of the enclosure and the heating unit and in communication with the latter, a warm air conduit underlying said platform and opening at one end portion into said warm air flue, there being spaced-apart discharge openings in said platform and conduit progressively increasing in size toward the return flue, said conduit being gradually decreased in cross-sectional area toward said return flue, and a cooled air flue on each side of said platform and having openings therein for the admission of cooled air from said enclosure, said cooled air conduits extending between both flues and opening at their rear ends into said return flue at the opposite end of the kiln from the connections between the warm air flue and warm air conduit, and said cooled air conduits being gradually increased in cross-sectional area toward the return flue.

4. A lumber kiln, comprising an enclosure having an elongated, tracked platform therein, removable transverse partitions within said enclosure to divide the interior of the same into compartments, a heating unit adjacent said enclosure, a warm air flue, a cooled air return flue, said flues extending between opposite ends of the enclosure and the heating unit and in communication with the latter, a warm air conduit underlying said platform and opening at one end portion into said warm air flue, there being spaced-apart discharge openings in said platform and conduit progressively increasing in size toward the return flue, said conduit being gradually decreased in cross-sectional area toward said return flue, and a cooled air flue on each side of said platform and having openings therein for the admission of cooled air from said enclosure, said cooled air conduits extending between both flues and opening at their rear ends into said return flue and said cooled air conduits being gradually increased in cross-sectional area toward the return flue.

In testimony whereof, I affix my signature.
JAMES ALLEN WORDEN.
